CLAIM

The ornamental design for a watch band, as shown and described.

DESCRIPTION

FIG. 1 is a perspective view of a watch band showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another front view of a watch band of FIG. 1, depicted in an attached configuration with a watch face.

The broken lines in the drawings represent portions of the watch band and form no part of the claimed design. The broken lines immediately adjacent to the shaded areas define the bounds of the claimed design. The broken lines in FIG. 9 showing a watch face represent environmental subject matter only and form no part of the claimed design.
